UNITED STATES PATENT OFFICE

JOHN H. CUMMINS, OF DALLAS, TEXAS

SHIP

Application filed February 6, 1928. Serial No. 252,213.

The present invention relates to improvements in the construction of boat and ship hulls, and the primary object of the invention is to provide an improved construction for ship hulls designed for increasing the speed of ships and decreasing the pitch and roll of ships designed for sea going travel.

A further object of the invention is to provide an improved construction for ship hulls embodying an arrangement whereby large sea going ships or vessels may have increased speed with a minimum amount of pitch and roll when traveling rough seas.

A further object of the invention is to provide an improved ship hull construction embodying an emergency rudder so located as to permit of a relatively short turn being made by the ship when operated in conjunction with the usual rudder located at the stern of the ship.

A further object of the invention is to provide an improved hull construction for ships embodying an arrangement whereby auxiliary propellers and an emergency rudder may be disposed substantially amidship of the hull in alignment longitudinally of the hull with the aft propellers and rudder.

A still further object of the invention is to provide an improved ship hull construction which may be embodied in ships now in use thru a remodeling of a portion of the hull, and one wherein auxiliary propellers and an emergency rudder disposed substantially amidship will have a like action upon the water as that of the usual aft propellers and rudder.

Other objects and advantages of the invention will be apparent during the course of the following detailed description, taken in connection with the accompanying drawings forming a part of this specification and in which drawings:

Figure 1 is a side elevation of the ship provided with the improved hull construction.

Figure 2 is a bottom plan view of a hull constructed as shown in Figure 1.

Figure 3 is a fragmentary section on line 3-3 of Figure 1.

Figure 4 is a side elevation of a ship hull

constructed in accordance with this invention and showing an arrangement for relieving strain between the fore and aft hull sections; the view also being one illustrating an arrangement whereby existing types of ship hulls may be remodeled to embody the features of this invention.

Figure 5 is a bottom plan view of the hull as illustrated in Figure 4.

Figure 6 is a fragmentary vertical section on the line 6-6 of Figure 4.

In the drawings, like reference characters designate corresponding parts throughout the several views.

Referring first to the type of ship construction as illustrated in Figures 1, 2 and 3, the letter A may designate as a whole the improved type of ship, embodying a hull or body portion B constructed in accordance with this invention.

The hull or body B, beneath the water line 10 is formed amidship with a transverse way or undercut 11 forming fore and aft hull sections 12 and 13 respectively provided with longitudinally aligning keels 14 and 15. The forward hull section 12 is provided with a wedge like fore part or entrance 16, and at its rear or stern end is formed with a transversely arcuated stern portion 17 forming a forward wall defining the transverse way 11. Thus it will be seen that the fore hull section 12 forming the forward portion of the hull B conforms to an ordinary boat hull formation having a wedge like bow and an arcuated stern portion.

The aft hull section 13, and which is connected with the fore hull section by a bridge portion 18, is of a like thickness or beam as that of the fore hull section. The bow or forward end of the hull section 13 is formed with a wedge like portion or entrance 19, and a transversely arcuated stern portion 20. Thus it will be seen that each of the hull sections 12 and 13 embodies an entrance and a counter, with the counter 17 and the entrance 19 of the hull sections 12 and 13 respectively forming the fore and aft bounds of the transverse way or undercut 11. As will be observed, the cutwaters 21 and 22 of the hull sections are arranged in alignment longitudinally of the

hull B so that each of the entrances 16 and 19 will act to spread the water in a like manner to opposite sides of the ship during travel.

The overhang 23 has its under surface arranged at an elevation above the under surface of the bridge portion 18 and it will be observed that the bridge portion 18 acts as an overhang for the counter 17.

Mounted beneath the overhang 23 at the counter 20 is a stern rudder 25 which may be operated in any desired manner, and this rudder will act for steering the ship thru normal running conditions. Extending from the counter 20 at opposite sides of the rudder 25 are propellers 26 which may be driven by suitable mechanism arranged within the hull section 13. These twin stern propellers 26 as will be observed are located at opposite sides of the longitudinal center of the hull B, while the rudder 25 is arranged at the longitudinal center of the ship in alignment with the aligning keels 14 and 15.

Mounted in the transverse way 11 as upon a shaft 27 projecting downwardly thru the bridge portion 18, is an emergency rudder 28 which may be operated independently of the stern rudder 25 or operated in conjunction therewith when desiring to make a relatively short turn. This rudder 28 is arranged in the way 11 at the longitudinal center of the hull B and preferably at a location substantially midway between the counter 17 and cutwater 22. Extending rearwardly thru the counter 17 at opposite sides of the keel 14 are suitable propeller shafts for mounting of a pair of auxiliary propellers 30 within the transverse way 11. By observing Figure 2 it will be seen that these auxiliary propellers 30 will act upon the water in substantially a like manner as that of the stern propellers 26 and that the water directed rearwardly by the propellers 30 will strike the wedge like surfaces of the entrance 19 which will not form any appreciable obstruction for the water being directed rearwardly by the propellers 30. It will further be observed in Figure 2 that the transverse way 11 is bounded by formations corresponding to the fore and aft formations of the hull B so as to permit the auxiliary propellers 30 to properly operate and permit the emergency rudder 28 to function for steering the ship with or without the aid of the stern rudder 25. Thus it will be seen that should the stern rudder 25 be broken or otherwise rendered inoperative, the emergency rudder 28 arranged amidship, may be operated for steering the ship. The propellers 30 may be driven by suitable machinery arranged in the fore hull section 12.

Referring now to Figures 4, 5 and 6, and wherein an arrangement has been shown whereby the hull will be strengthened by means of suitable bracing for preventing vibration and reducing strain on any sections 65 of the hull, the ship A' has been shown as em-

bodying a hull or body portion B' provided in its underside with a transverse way or undercut 11' forming fore and aft hull sections 12' and 13' respectively. Extending throughout the length of the hull or body B', and spanning the transverse way or undercut 11' is a keel girder 35 forming a tie between the hull sections 12' and 13' along their keel portions.

The hull sections 12' and 13' are of like external formation as that of the ship construction illustrated in Figures 1, 2 and 3, and are formed respectively with entrances 16' and 19' and counters 17' and 20'. Extending from the sides of the counter 17' to the entrance 19' are starboard and port side longitudinal girders 36 which act to further brace the fore and aft hull sections. These longitudinal girders 36 may extend throughout the length of the hull B' as shown by the dotted lines in Figure 4.

Traversing the hull at the way 11 is a suitable number of cross and vertical ribs or girders 38 which are connected at their medial horizontal portions to the keel girder 35 and have their vertical portions secured to the longitudinal girders 36 so that the girders 35, 36 and 38 form an open net work structure connecting the hull sections beneath the bridge portion 18'. Thus it will be seen that the girders 35, 36 and 38 will act to reduce strain on the bridge portion 18'.

Arranged beneath the overhang 23' is a stern rudder 25', and arranged at each side of the rudder is a screw propeller 26'. Arranged within the transverse way or undercut 11' is an emergency rudder 28', the lower end of the rudder shaft of which may be mounted in the keel girder 35 if so desired. Arranged also within the way 11' are the auxiliary screw propellers 30' which are mounted in the counter 17' of the forward hull section 12'. Thus it will be seen that the strengthening girders 35, 36 and 38 form a protecting net work about the rudder 28' and propellers 30', and by reason of the open net like structure of the girders, the rudder and propellers are permitted to properly operate.

In the remodeling of ships already built, the girder beam 35, the starboard and port side longitudinal girders 36, and the cross and vertical ribs or girders 38 may constitute usual sections of the hull structure, and could be left intact as a bracing means for the hull sections when the hull is reconstructed to provide the transverse way or undercut 11' for accommodating the emergency rudder and auxiliary propellers. Thus it will be seen that boats of existing construction may be altered to embody the features of this improved type of hull construction without involving a considerable expense.

Thus it will be seen that by so constructing the hull with fore and aft sections of like

external contour separated by a transverse way disposed substantially amidship, that the hull is designed as a wave straddler such as will minimize the pitch and roll of the ship when traveling rough seas, and that by 5 so utilizing the transverse way to accommodate an emergency rudder and auxiliary propellers, that increased speed will be obtainable.

By so having the under surface of the 10 bridge portion connecting the hull sections disposed below the waterline, which prevent likelihood of the emergency rudder and auxiliary propellers leaving the water when the ship is traveling at a relatively fast rate 15 of speed.

From the foregoing description it will be apparent that a novel and improved construction for ships has been disclosed having a hull structure so shaped as to decrease the 20 pitch and roll of the ship when traveling rough seas, and which specific hull construction provides means for the disposing an emergency rudder and auxiliary propellers at a point substantially amidship so that 25 increased speed is obtainable. It will further be apparent that a novel hull construction has been provided embodying fore and aft hull sections of like general formation and thus allowing for proper and efficient 30 operation of the rudder and propellers which are located amidship.

Changes in detail may be made to the forms of invention herein shown and described, without departing from the spirit of the invention or the scope of the following claims. 35

I claim:

1. In a ship construction a hull embodying spaced fore and aft hull sections connected in longitudinal alignment by a bridge portion and providing a transverse undercut extending between the hull sections beneath the bridge portion, said hull sections being of like external outlines and each having an entrance and a counter, propellers mounted in 45 the counter of each hull section one to each side of the longitudinal center of the hull, and a rudder mounted rearwardly of each counter at the longitudinal center line of the hull.

2. In a ship construction a hull having a transverse undercut forming spaced fore and aft hull sections connected in longitudinal alignment by a bridge portion, said hull sections being of like external outline below the 55 bridge portion, said undercut being of a length longitudinally of the ship less than the length of either hull section, a rudder disposed at the stern of the aft hull section, and rudder and propeller means disposed at the 60 stern of the forward hull section.

3. In a ship the combination of a hull having a transverse undercut forming spaced fore and aft hull sections connected in longitudinal alignment by a bridge portion, propellers mounted at the stern of each hull sec-

tion, a rudder mounted at the stern of each hull section and an open frame work structure spanning the undercut about the propellers and rudder arranged therein and serving to brace the hull sections.

4. In a ship the combination of a hull having a transverse undercut forming spaced fore and aft hull sections of like external outline, a keel girder connecting the hull sections and spanning the undercut, longitudinal 75 girders connecting the hull sections at each side of the keel girder, spaced apart ribs connecting the keel girder and longitudinal girders and conforming to the cross sectional outline of the hull sections, a stern rudder for 80 the ship, an emergency rudder arranged in the undercut between the hull sections, and propellers arranged at the stern of each of the hull sections.

5. In a ship the combination of a hull provided with a transverse undercut arranged amidship and forming spaced fore and aft hull sections of like external outline, an open frame work bridging the undercut and connecting the hull sections beneath a bridge 85 portion connecting the upper portions of the hull sections, rudder and propeller means arranged at the stern of the aft hull section, and rudder and propeller means arranged in the undercut at the stern of the forward hull 90 section and independently operable from the rudder and propeller means arranged at the stern of the aft hull section.
